CLAIM

The ornamental design for a leash with suction cup, as shown and described.

DESCRIPTION

FIG. 1 is a front elevational view of a leash with suction cup showing my new design, the rear elevational view being substantially the mirror image thereof;

FIG. 2 is a left side elevational view, the right side view being the mirror image thereof;

FIG. 3 is a top plan view thereof;

FIG. 4 is a bottom plan view thereof;

FIG. 5 is a front elevational view of a second embodiment thereof;

FIG. 6 is a right side elevational view, the left side being the mirror image thereof;

FIG. 7 is a rear elevational view thereof;

FIG. 8 is a top plan view thereof; and,

FIG. 9 is a bottom plan view thereof.

FIG. 1

FIG. 2

FIG. 3
